UNITED STATES PATENT OFFICE

164,067

CHILD'S PEDAL VEHICLE

Harry Sebel, London, England

Application February 28, 1951, Serial No. 14,341
In Great Britain January 8, 1951

Term of patent 14 years

(Cl. D34—15)

To all whom it may concern:

Be it known that I, Harry Sebel, a subject of the King of Great Britain, residing at London, England, have invented a new, original, and ornamental Design for a Child's Pedal Vehicle, of which the following is a specification, reference being had to the accompanying drawings, forming part thereof.

Fig. 1 shows a three quarter front perspective view of a child's pedal vehicle, showing my new design;

Fig. 2 shows a front view thereof;

Fig. 3 shows a rear view thereof;

Fig. 4 shows a three quarter rear perspective view; and

Fig. 5 a plan view thereof.

I claim:

The ornamental design for a child's pedal vehicle, as shown.

HARRY SEBEL.
